UNITED STATES PATENT OFFICE.

RUDOLF MÜLLER VON BERNECK, MARTIN MOEST, AND HUGO GRAF, OF HÖCHST-ON-THE-MAIN, GERMANY, ASSIGNEES TO FARBWERKE VORM. MEISTER LUCIUS & BRÜNING, OF HÖCHST-ON-THE-MAIN, GERMANY, A CORPORATION OF GERMANY.

PROCESS OF MANUFACTURING PURE NITRIC OXID.

1,021,234.

Specification of Letters Patent. Patented Mar. 26, 1912.

No Drawing.

Application filed May 10, 1911. Serial No. 626,191.

To all whom it may concern:

Be it known that we, RUDOLF MÜLLER VON BERNECK and MARTIN MOEST, Ph. D., and HUGO GRAF, Ph. D., citizens of the Empire of Germany, residing at Höchst-on-the-Main, Germany, have invented certain new and useful Improvements in the Process of Manufacturing Pure Nitric Oxid, of which the following is a specification.

10 It is known that by the electrolysis of nitric acid in the cathode compartment of an electrolytic cell various products can be obtained. By using diluted nitric acid at a moderate temperature there are produced 15 substantially ammonia and at the same time some other products of reduction of the nitric acid, among them even elementary nitrogen. According to the process described in U. S. Patent No. 887,266, when nitric acid 20 is heated and subjected to the action of the electric current, it evolves at the cathode the easily-condensable nitrogen dioxid, or a mixture of nitrogen dioxid and nitric oxid. However, all endeavors to modify the process 25 so as to obtain pure nitric oxid (NO) have been hitherto unsuccessful. We have now made the surprising observation that when the nitric acid to be subjected to electrolysis at the cathode contains nitrous acid, 30 a nearly chemically pure nitric oxid (99-100 per cent. strength) is obtained in almost quantitative yield. In the following specification there are always implied by "nitrous acid" also the nitric oxids N_2O_3 and 35 $NO_2(N_2O_4)$, which form in presence of water nitrous acid.

40 The formation of the nitric oxid is substantially due to the reduction of the nitric acid, while the nitrous acid present is attacked only to a very small extent, so that there is possibly a catalytic action of the nitrous acid. As electrodes may be used carbon or graphite, or the metals capable of resisting attack by nitric acid, such as gold 45 or platinum. Among these materials carbon or graphite, and platinum or its alloys, have proved to be most suitable. These electrodes require a comparatively weak tension and furnish entirely pure nitric oxid, 50 whereas, when using certain other electrodes,

for instance aluminium electrodes, some other products of reduction of the nitric acid are produced causing losses of nitrogen. There is also required, under otherwise similar conditions, a considerably 55 higher tension at the electrodes when aluminium cathodes are used.

The concentration of the nitric acid used may vary within wide limits; however it is advantageous not to exceed a percentage 60 of 40, because otherwise nitrogen dioxid is formed in addition to nitric oxid, especially at a raised temperature. The percentage of nitrous acid contained in the nitric acid may also be considerably varied, but even 65 1% or less suffices to give favorable results. It is remarkable that the minimum amount of nitrous acid, in order to obtain a pure nitric oxid, depends on the material used for the electrode, the conditions of the electric current and the concentration of the nitric acid. For instance when nitric acid of 20-30 per cent. strength and a current-density of 5-10 amperes per square decimeter are used at ordinary temperature, the 70 said minimum amount of nitrous acid is: for cathodes made of carbon (graphite), below 1% of HNO_2 ; for cathodes made of platinum-foil, about 1.2% of HNO_2 ; for cathodes made of gold-platinum alloy, about 75 1.9% of HNO_2 . It is advisable to keep the temperature moderate.

The anode compartment is preferably charged for instance with nitric acid containing nitrous acid, in which case the anodic oxygen is used in oxidizing the nitrous acid, with formation of nitric acid. Of course, there may also be used other suitable electrolytes in the anode compartment, for instance sulfuric acid or nitric acid. 85 90

The present process has the advantage that the nitric oxid, which has not been obtainable hitherto by electrolysis in a pure form, can be produced in a very cheap way and pure state while avoiding losses of nitrogen. The nitric oxid thus obtained can be easily dried, for instance by means of concentrated sulfuric acid. By adding a corresponding quantity of pure dry oxygen or a suitable dry mixture of gases contain- 95 100

ing oxygen, for instance air, it is possible to prepare nitrogen dioxid absolutely free from nitric acid and easily condensable. In this pure liquid form it is fit for transport 5 and for being made up into other products.

Having now described our invention what we claim is:

The process of preparing pure nitric oxid (NO) by electrolysis, which consists in 10 subjecting nitric acid containing nitrous

acid to electrolysis at a cathode capable of resisting attack by nitric acid.

In testimony whereof, we affix our signatures in presence of two witnesses.

RUDOLF MÜLLER VON BERNECK.

MARTIN MOEST.

HUGO GRAF.
